UNITED STATES PATENT OFFICE.

GABRIEL MARIE ROUGE, OF GENEVA, SWITZERLAND, ASSIGNOR TO PATEK
PHILIPPE & CO., OF SAME PLACE.

DESIGN FOR A WATCH-BRIDGE.

SPECIFICATION forming part of Design No. 22,365, dated April 25, 1893.

Application filed October 27, 1892. Serial No. 450,186. Term of patent 14 years.

To all whom it may concern:

Be it known that I, GABRIEL MARIE ROUGE, a Swiss citizen, a member of the firm of Patek Philippe & Co., watch-manufacturers, residing at Geneva, Switzerland, have invented a new and original Design for Watch Plates or Supports for Watchworks, of which the following is a specification.

The drawing shows the design of the watch
bridges and plates.

The leading feature of this design for watch work supports consists of the design of the reverse curved and parallel edges of the bridge upon the circular plate. The plate B of the watch is circular and the plate D has a circular outer edge parallel to the edge of the plate B and a curved inner edge, as represented. The curved edges 1, 2, 3, 4, 5, 6, of

the bridges are substantially parallel to each other, the round ends 7, 8, 9 have reversed 20 curves at 11, 12, 13, and the outer ends of the bridges are arcs of a circle parallel to the circular edge of the plate B. The openings between the edges 2 and 3 and 4 and 5 are parallel sided. 25

I claim—

In the design for the supports for watch-works, the design of the group of bridges, as described and shown.

In testimony whereof I have signed my 30 name to this specification in the presence of two subscribing witnesses.

GABRIEL MARIE ROUGE.
